E. PELTON & S. D. HOPTON.
FEED WATER HEATER FOR STEAM BOILERS.
APPLICATION FILED MAR. 28, 1913.

1,092,592.

Patented Apr. 7, 1914.

UNITED STATES PATENT OFFICE.

ERNEST PELTON AND STANLEY D. HOPTON, OF GENEVA, OHIO.

FEED-WATER HEATER FOR STEAM-BOILERS.

1,092,592.

Specification of Letters Patent.

Patented Apr. 7, 1914.

Application filed March 28, 1913. Serial No. 757,355.

To all whom it may concern:

Be it known that we, ERNEST PELTON and STANLEY D. HOPTON, citizens of the United States, residing at Geneva, in the 5 county of Ashtabula and State of Ohio, have invented certain new and useful Improvements in Feed-Water Heaters for Steam-Boilers, of which the following is a specification.

10 Our invention comprises an improved feed water heater and oil and vapor separator for steam boilers, and the invention is of especial utility in heating the supply water furnished to the main feed pump of the feed 15 water system of a steamship without causing the said pump to be air or vapor bound. In other words the invention comprises an improved heater adapted to be used as an auxiliary to the main heater of a feed water 20 system, thereby securing economy and greater efficiency in operation, all substantially as shown and described and particularly pointed out in the claims.

In the accompanying drawings, Figure 1 25 is a diagram showing the invention embodied in a feed water installation, and Fig. 2 is a sectional view of the heater and its immediate connections.

Having reference now particularly to Fig. 30 1, A represents a hot well which receives the condensed steam from a steam engine on board a ship, and from which the water is discharged by suitable apparatus as usual. Connected with the hot well is a stand-pipe 35 which furnishes a head for the water in the hot well from which the feed water for the boiler is constantly supplied when it is not otherwise taken from the sea. The air and vapors rising in the condenser of the 40 engine and which otherwise might make the feed water system steam or air bound, are also conveyed away by the stand pipe.

In taking the feed water from the hot well A, a main feed pump B is used to deliver it to a heater C before forcing it into the boiler. Our heater (represented by 2) is designed to be used as an auxiliary to main heater C and is placed in the suction line of pipe 3, 3', between the hot well A 50 and pump B.

Heretofore and so far as we are aware it has not been found practicable to heat the water to high temperatures on the supply side of the main feed pump and maintain a solid stream of water without seriously affecting the operation of the pump;

but with a heater and separator of the kind herein set forth, the water can be successfully heated to a very high temperature as it comes from the hot well A and is delivered to the main feed pump B under the pressure of the head of water in the stand-pipe, all without affecting the operation of the pump. Thus it occurs that when the water is discharged by pump B to the 60 surface heater C and there further heated that a materially higher temperature is obtained for the water discharged into the boiler than by use of the main heater alone as is the general practice. In fact, with 65 our invention the water which is delivered to the pump may be heated to 200° Fahrenheit or higher before it is discharged into the main heater C which raises the temperature of the water still higher (approximately 70 to the temperature of the exhaust steam) before it enters the boiler, thereby working great economy in fuel consumption.

In detail our heater comprises a cylinder 2 having a short intake pipe 4 at its bottom 80 connected with a coupling 5 into which the water from the hot well is discharged by a short pipe 6. The coupling member 7 for pipe 6 supports a perforated pipe 8 which extends lengthwise into pipe 6 and is used to jet exhaust steam into the water in its 85 passage through said pipe. A valve 9 controls the flow of exhaust steam which is obtained from the auxiliary steam lines of the ship by a pipe 9' coming from the auxiliary 90 steam connection for main heater C. Cylinder 2 is also provided with a water discharge pipe 10 which in effect is an extension of the discharge pipe 3' leading to pump B. Pipe 10 extends downwardly from 95 the upper head of cylinder 2 to about the middle so that the intake end of said outlet pipe 10 is beneath the zone where air or uncondensed vapor would naturally accumulate when taken into the cylinder as occurs 100 when the exhaust steam is forced into the water by jet pipe 8. A shield 12 which divides the heater 2 into an upper and a lower chamber and which is of cup shape or conical form is supported by a pipe 13 below 105 and about the mouth of the said pipe 10, and this shield therefore forms something of a trap for sediment, but its main function is to guard against escape of air and vapors through pipe 10. In other words the 110 water at the intake end of suction pipe 10 will be guarded and kept free from dis-

turbance by this shield from the action of the steam jet 8 on the water, particularly as vent and relief for the air and vapors is afforded at the top of this heater by a pipe 5 14 having one or more branches or elbows 15 connecting with pipe 14. The said pipe 14 extends to a considerable level above the normal head of water in the stand-pipe α and may be provided with a valve at some point 10 in the line thereof if desired, but no valve is shown as it is designed to keep the pipe 14 open to the atmosphere. However, said pipe has an overflow pipe 16 (Fig. 1) connected therewith at a point slightly below the normal 15 head of water to draw off the oil or other accumulations which rise to the top of the heater and enter pipe 14. It will be understood that in the course of operations more or less grease or oil will accumulate in 20 the steam and water connections, which objectionable substances should be eliminated before returning the water of condensation to the boiler.

Other features are a valved clean-out pipe 25 17 at the side and top of cylinder 2, and a valved sediment clean-out pipe 13 from shield or cup 12 through pipe 4 and the bottom of coupling 5. The shield should be cleaned out occasionally or it will become 30 filled with sediment which will be carried forward to the boiler. However, the location of the said shield at about the middle of the heater and the relatively narrow space between the shield and cylinder wall 35 helps materially to prevent sedimentary accumulations from rising in the lower chamber to the overflow point into said shield and the main sedimentary deposits naturally gravitate to the bottom of the cylinder, and 40 this sediment gathering in the bottom of the cylinder can be drawn off through the valved connection 19, whereas the sediment in the pipe 6 can be removed through valved connection 20. Therefore, this device also 45 serves as a water purifier.

What we claim is:

1. A feed water heater for steam boilers comprising a cylinder having a discharge pipe extending downwardly into the same 50 and provided with means to produce a downward flow of water in said cylinder before escaping through said pipe, in combination with a steam jet to heat the water flowing to said cylinder discharge pipe, and a vent pipe 55 opening directly into the upper end of said cylinder, for the air and vapor.

2. An auxiliary heater for feed water

for steam boilers comprising a cylinder having a water intake connection, an outlet pipe extending into said cylinder, a sediment trap and shield to guard the mouth end of said pipe, and a discharge connection at the upper end of said cylinder for the air, vapor and oil which is trapped therein. 60

3. In a feed water heater for boilers, a cylinder having a water supply connection provided with a steam jet to heat the water passing therethrough, a centrally located shield in said cylinder slightly spaced apart from the walls thereof and subdividing said cylinder into upper and lower chambers, a water discharge pipe and a vapor discharge connection for the upper chamber, and a valved connection for the lower chamber to permit removal of sedimentary deposits. 65

4. In a feed water heater for boilers, a water receptacle having a water supply connection at its bottom and a discharge pipe extending part way into the receptacle from the top, a shield about the end of said pipe having a pipe support adapted to draw off accumulating sediment, and pipe connections with the top of said heater providing an escape for vapor, oil and other objectionable accumulations from the heater. 70

5. In feed water heating apparatus for steam boilers, a water receptacle having a water intake pipe, a steam jet within said pipe, a valved connection to withdraw sedimentary deposits from said pipe, a water discharge pipe extending into said receptacle, a shield for the mouth of said discharge pipe, a valved connection to remove sedimentary deposits from said shield, and a vent pipe for the air and vapors accumulating within said receptacle. 75

6. A feed water heating apparatus for steam boilers adapted to be used on the suction side of the feed pump, comprising a water receptacle having a water supply connection, a steam jet to heat the water, a water discharge connection, and a vapor outlet pipe opening directly into said receptacle and extending above the normal head of water supply and being open to the atmosphere. 80

In testimony whereof we affix our signatures in presence of two witnesses.
